UNITED STATES PATENT OFFICE.

GEORGE P. TILTON, OF NEWBURYPORT, MASSACHUSETTS, ASSIGNOR TO THE FOWLE MANUFACTURING COMPANY, OF SAME PLACE.

DESIGN FOR A SPOON.

SPECIFICATION forming part of Design No. 21,357, dated February 16, 1892.

Application filed July 11, 1891. Serial No. 399,212. Term of patent 7 years.

To all whom it may concern:

Be it known that I, GEORGE P. TILTON, a citizen of the United States, residing at Newburyport, in the county of Essex and State of Massachusetts, have invented and produced a new and original Design for the Handles of Spoons, of which the following is a specification.

Reference is to be had to the accompanying drawing, forming a part of this specification, in which the figure represents a face view of a spoon having my new design embodied therein.

The design consists in the surface ornamentation shown, the leading feature of which is the equestrian figure of George Washington, as seen in front view, the same being indicated by the letter *a*, and the figures *b c d* representing, respectively, a dismounted canon, a fragment of the wheel thereof, and a cannon-ball, the said figures being suggestive of the termination of the American Revolution. In connection with the said main figures appear the minor figures *e e'*, representing olive-branches, the traditional symbols

of peace, the same harmonizing with the dismounted cannon and companion figures in carrying out the main idea of the design. The figure *e* appears near the outer end of the handle above the head of Washington, 30 while the figure *e'* and the figures *b c d* form a group. Inward from the group mentioned the fac-simile signature of George Washington appears ranging longitudinally of the handle. Said signature does not form part 35 of my invention.

The bowl ornamentation shown may be omitted, if desired, it not being essential. It consists of a view representing the evacuation by the British, November 25, 1783, and includes in the background the representations of ships and in the foreground a wharf with soldiers in the act of embarking. 40

I claim—

The design for the handles of spoons herein 45 shown and described.

GEORGE P. TILTON.
